GRAIN SAMPLER

Henry K. Holman, Washington, D. C.; dedicated
to the free use of the Public in the Territory of
the United States of America

Application January 4, 1937, Serial No. 118,980

1 Claim. (Cl. 83—15)

(Granted under the act of March 3, 1883, as
amended April 30, 1928; 370 O. G. 757)

This application is made under the act of
March 3, 1883, as amended by the act of April 30,
1928, and the invention herein described, if
patented, may be manufactured and used by or
5 for the Government for governmental purposes
without the payment to me of any royalty
thereon.

I hereby dedicate the invention herein de-
scribed to the free use of the Public in the terri-
10 tory of the United States of America to take effect
upon the granting of a patent to me.

My invention relates to a sampling device for
obtaining samples of grains stored in bulk in
15 tanks, bins, or other bulk grain storage contain-
ers and the object of the device hereinafter de-
scribed is to enable one to draw samples of grain
from such containers, without having to climb
down into them. I attain this object by the de-
20 vice illustrated in the accompanying drawing in
which Fig. 1 is a detailed view of the entire de-
vice showing the valve closed and the metal
point reversed in the tube to facilitate trans-
portation and Fig. 2 is another view of the device
25 with the valve open and the metal point posi-
tioned to sample grain.

The device consists of a metal tube 1, fitted
at one end with a solid metal point 2. This point
is held in place at the lower end of the tube by
means of two screws 3 on opposite sides of the
30 tube. These go through apertures in the tube,
and into threaded holes in the metal point 2.
When not in use, the screws 3 may be removed
and the metal point 2 reversed in the tube to
facilitate the transporting of the device, as
35 shown in Fig. 1.

At the open or top end of the tube is a valve
4 designed and positioned to close and open the
upper end of the tube. The valve is supported by
40 two rods 5 paralleling the sides of the tube 1.
These rods 5 are held in place by two sleeves 6 fas-

tened to and on opposite sides of the tube 1.
Rods 5 slide up and down through the sleeves 6.
The lower ends of the rods fit, when the device
is closed, into pockets 7, which are also fastened
to the tube 1.

When the valve is opened, the lugs 10 on the
lower ends of both rods 5 slide up against the
lower ends of sleeves 6 and stop. They are of a
size to prevent their passing through the sleeves.

A metal eye bolt 12 attached to and extending 10
upwardly from the valve 4 affords a means of
attaching a rope 13. The device, with rope
(one end is held by operator) attached, when
dropped through an opening into a bin contain- 15
ing grain, plunges into the grain. It penetrates
beneath the top surface of any grain in a bin
sufficiently deep ordinarily to reach grain that
is not chaffy. After maximum penetration has
been attained, the operator gives the rope a steady
pull. This opens the intake valve 4 allowing 20
grain at that point to fill the container of the
device through the opening 11, shown in Fig. 2.
This requires but a few seconds. Next by means
of the rope the operator withdraws the device
filled with the desired sample of grain, from the 25
bin.

Having fully disclosed my invention, I claim:

A grain sampling device comprising a tube, a
removable weighted point fitted closely into, at-
tached to and extending downwardly from one 30
end of the tube, a valve at the other end of the
tube designed and positioned to open and close
that end of the tube, rod members rigidly at-
tached to the valve and slidingly secured to the
walls of said tube, means attached to the valve 35
to move said rod members along the sides of the
tube and means attached to the tube and rod
members to limit the movement of said rod
members.

HENRY K. HOLMAN. 40
